Fig. 1. 25

25

A technical drawing of a geological cross-section. The left side features a vertical scale with markings 1, 2, 6, 5, 24, 20, 19, 17, and 16. The right side features a horizontal scale with markings 5, 6, and 3. The cross-section shows a layered rock formation with a hatched pattern. A vertical line with a circular top is positioned on the left side of the diagram.

UNITED STATES PATENT OFFICE

HARTWELL G. CHADBOURNE, OF SEATTLE, WASHINGTON

FIREPLACE SCREEN

Application filed May 28, 1929. Serial No. 266,627.

This invention relates to a fireplace screen.

The object of my invention is the production of an ornamental, useful and efficient screen, for a fireplace, which will prevent sparks or burning pieces of material from falling out of the fireplace onto the floor.

Another object of the invention is the construction of a screening device for a fireplace, which preferably has two roller units that are manipulated for closing the front of a fireplace with a fine wire or metal mesh, but which can be operated with ease for placing the screening means out of the way, leaving free access to the fireplace.

With the foregoing and other objects in view, my invention comprises certain novel constructions, combinations and arrangements of parts as will be hereinafter fully described, illustrated in the accompanying drawings, and more particularly pointed out in the appended claims.

In the drawings:

Figure 1 is a view in front elevation, of an apparatus constructed in accordance with the present invention, showing the same applied to a fireplace.

Figure 2 is a sectional view taken on lines 2, 2, Figure 1 and looking in the direction of the arrows.

Figure 3 is an enlarged sectional view taken on line 3, 3, Figure 1.

Figure 4 is an enlarged sectional view taken on line 4, 4, Figure 1, and looking in the direction of the arrows.

Figure 5 is a sectional view taken on line 5, 5, Figure 3, and looking in the direction of the arrows.

Figure 6 is an enlarged, fragmentary sectional view of the hollow track and part of one of the hangers.

Referring to the drawings by numerals, 1 designates the tubular-like casings, connected by a hollow slotted track 2. Each casing 1 is provided with a lower bearing device 3.

45 The lower bearing device 3 (Fig. 3) comprises a threaded post 5 that extends down into the plastic hearth 6, with nut 7 screwed on post 5 against the bottom 8 of the casing 1. Nut 7 is seated down in the hearth. A bearing containing casing 9 is provided with

ball bearings 10 on which the lower end of roller 11 revolves. The upper end of post 5 extends into the roller 11 to keep it centered on the bearing containing casing 9.

A disc 11^a is in the top portion of casing 1, and stub shaft 12 extends into same. The end of track 2 extends into the casing 1 and rests on the disc 11^a. A threaded bolt 13 extends through bracket 14 in the top of casing 1, and into the top of the track. The upper end of bolt 13 is fixedly secured within the ornamental knob 15. Bolt 13 locks the track within the casing, thereby keeping the parts assembled. Both of the casings and co-operating parts are similarly constructed. On roller 11 is a wire mesh screening 16, which is adapted to be drawn out of casing 1 through the vertical slot 17; the slots 17 are in alignment and register with slot 29 of track 2.

Each of the two casings 1 are fastened to the fireplace by an anchor device 18. This anchor device comprises a band 19 extending around the casing and fixedly secured to the vertical plate 20. This plate 20 is held in position against the face of the fireplace by bolt devices. Each bolt device comprises a sleeve 21, slotted at its inner end for expandable wings 22. These wings are separate and independent, and are forced outwardly by the wedge bolt 23 being drawn outwardly by screwing nut 24 inwardly, upon the outer threaded end of the bolt. Right here, it is to be noted that in the upper bearing device structure, the end of track 2 acts as a filler between disc 11 and bracket 14, holding the disc properly for constituting a bearing for the upper end of the roller 11.

I provide a central track support 25 (Fig. 4), which comprises a band 26 that is fixedly secured to a substantially U-shaped bracket 27, and this bracket is held against the face of the fireplace by means of said bolt device. In this manner, the central part of the hollow track is efficiently supported, producing a very durable structure.

To the outer vertical edge of each sheet-like wire mesh 16, is secured a hanger device. This hanger device comprises two metal strips 28 between which the mesh 16 is se-

cured. The upper ends of the hanger devices extend through slot 29 in the bottom of the hollow track 2, and bolts 30 extend through these ends, within the track 2, with rollers 31 thereon. Handles 32 are fastened to the middle of the hangers constituted by said strips or plates 28, and a latch device 33 is employed for holding the hangers together and the wire mesh or screening in front of the fireplace opening.

The rollers 11 are of the usual hollow spring-carrying type, working similar to the ordinary window shade roller, so that the mesh sheets may be drawn out of the casings, but upon the latch device 33 being released, the spring action is sufficient to wind the wire mesh sheets upon the roller, with the hangers substantially out of the way, leaving practically the whole of the fireplace opening free and unobstructed. I have found from practical experience that the hangers travel easily upon the track, and that the entire operation of my device is simple and efficient.

From the foregoing, it will be understood that broadly I have provided a fireplace screen or apparatus in which a plurality of casings, containing spring actuated rollers are used, each casing provided with hearth anchoring means, as well as anchoring means for securing the casings to the vertical face of the fireplace; that there is a central track support, besides the track being anchored at its ends within said casings. Broadly speaking, the wire mesh constitutes flexible screens adapted to be rolled within the casings and extended and locked together for completely covering the opening of the fireplace.

While I have described the preferred embodiment of my invention and illustrated the same in the accompanying drawings, certain minor changes or alterations may appear to one skilled in the art to which this invention relates, during the extensive manufacture of the same, and I, therefore, reserve the right to make such alterations or changes, as shall fairly fall within the scope of the appended claims.

What I claim is:

1. In a fireplace screen, the combination of a pair of hollow metallic casings, adapted to be placed at opposite sides of a fireplace opening, a hollow metallic track having its ends extending into and supported in the tops of said casings, said track and casings provided with slots in the same vertical plane and in their inner faces, roller screens normally in said casings and mounted to slide in the slots of said casings, and supports secured to said screen and slidably mounted in the slot of said track.

2. In a fireplace screen, the combination of a pair of hollow vertical casings adapted to be placed at opposite sides of a fireplace opening, said casings provided on their inner faces with slots, a horizontal hollow track connect-

ing said casings and having its ends enclosed by and secured within the tops of said casings, said track provided with a slot in its under face in rectangular arrangement with said slots of said casings, roller screens in said casings and adapted to move in the slots of said casings, hanger devices secured to said roller screens, and said hanger devices in the slot of said track in rectangular arrangement with the slots of said casings, substantially as shown and described.

In testimony whereof I hereunto affix my signature.

HARTWELL G. CHADBOURNE.
